(57) **CLAIM**

The ornamental design for a combined bowl and insert support components, as shown and described.

DESCRIPTION

FIG. 1 is a top and front perspective view of a combined bowl and insert support components showing my new design;

FIG. 2 is a top plan view thereof;

FIG. 3 is a front elevation thereof;

FIG. 4 is a top plan view of the insert base component with the bowl and insert components omitted for ease of illustration;

FIG. 5 is a side elevation thereof;

FIG. 6 is a front elevation of an insert component;

FIG. 7 is a side elevation thereof;

FIG. 8 is a top plan view thereof; and,

FIG. 9 is a front elevation of the insert base component with two insert components thereof.
